To all whom it may concern:

Be it known that I, GEORGE L. Fig. 1 is a front perspective view of the boot showing my new design as applied to a boot of substantially knee length;

Fig. 2 is a fragmentary showing of the upper portion of Fig. 1 looking at the side opposite to that shown in Fig. 1.

My design consists in the shape of the upper with a form fitting appearance at the ankle and along the instep and upwardly therefrom along the leg portion nearly to the knee and said upper having at the front and along the ankle and instep, portions which have the appearance of laterally separable flaps which are held together in edge to edge relation by a series of external fasteners with the slit or opening between the flaps and also the upper ends of the flaps appearing to terminate part way up the leg portion of the boot and the latter having the appearance of a continuous undivided wall above the upper end of the slit.

I claim:

The ornamental design for a rubber boot as shown and described.
